UNITED STATES PATENT OFFICE.

WILLIAM GORMAN, OF SOUTHBURY, CONNECTICUT, ASSIGNOR TO THE
PECK, STOW & WILCOX COMPANY, OF SAME PLACE.

DESIGN FOR THE ORNAMENTATION OF BUILDERS' HARDWARE.

SPECIFICATION forming part of Design No. 19,646, dated February 11, 1890.

Application filed December 11, 1889. Serial No. 333,361. Term of patent 14 years.

To all whom it may concern:

Be it known that I, WILLIAM GORMAN, a citizen of the United States, residing at Southbury, in the county of Hartford and State of Connecticut, have invented and produced 5 a new and original Design for the Surface Ornamentation of Builders' Hardware, of which the following is a specification, reference being had to the accompanying drawings, forming part thereof.

Figure 1 is a front elevation of a door pull and plate showing my design; Fig. 2, a like view of a drawer-pull showing my design; Fig. 3, a like view of a hinge showing my design; and Fig. 4, a like view of a sash-lift showing my design.

The invention relates to the surface ornamentation of builders' hardware, including the latch pull and plate, drawer-pulls, hinges, 20 sash-lifts, door-knobs, key-hole and knob escutcheons, and other articles, the four views illustrated being deemed sufficient to fully illustrate my design and its application to different articles of builders' hardware.

25 The leading feature of my design consists in the groundwork for the sunken surface of panels, the same being formed in narrow bars crossing each other at right angles and inclosing square depressions, and the broader ornamental bars crossing each other over said 30 surface and dividing it into larger squares.

In all of the figures, *a* designates the ground for the sunken surface of the panels, the same being formed of narrow bars crossing each 35 other and inclosing square depressions.

b designates a plain border that surrounds the sunken surface of each panel, and *c* larger ornamental bars extending over said ground surface *a* and dividing the same into

larger squares. Said bars are represented as 40 being interwoven, under and over each other, in imitation of basket-splints. In some instances I employ transverse parallel bars *d* to divide the panels, and between said parallel bars I arrange a row of circular ornaments *f*, as shown. The features thus described are the main features of my design, and if other ornaments are added in applying the design to different-shaped articles they should be such as would harmonize with the 45 design thus specifically described.

What I claim is—

1. The design for the surface ornamentation of builders' hardware herein shown and described, the same comprising the narrow bars 55 crossing each other in squares with inclosed depressions, a plain border surrounding the sunken surface of each panel, and larger ornamental bars extending over the ground surface and dividing the same into larger 60 squares, the transverse parallel bars, and intermediate row of circular ornaments, as set forth.

2. In the design for the surface ornamentation of builders' hardware herein shown and 65 described, the surface ornamentation of the panels, comprising the continuous unbroken narrow bars crossing each other in the form of squares with inclosed depressions, and the larger ornamental bars interwoven under and 70 over each other extending over said ground surface and dividing the same into larger squares, as set forth.

WILLIAM GORMAN.
